UNITED STATES PATENT OFFICE.

HARRISON B. WALTER, OF DANVILLE, ILLINOIS.

BUCKET OR PAIL.

1,233,150.

Specification of Letters Patent. Patented July 10, 1917.

Application filed November 18, 1914. Serial No. 872,815.

To all whom it may concern:

Be it known that I, HARRISON B. WALTER, a citizen of the United States, residing at Danville, in the county of Vermilion and State of Illinois, have invented certain new and useful Improvements in Buckets or Pails, of which the following is a specification.

This invention relates to an improvement 10 in buckets or pails constructed of paper, fiber board and the like, and the object is to provide removable ends made of the same material, which can be readily applied to the body of the receptacle.

15 The invention relates to still other novel features of construction and combinations of parts which will be hereinafter described and pointed out in the claims.

In the accompanying drawings:

20 Figure 1 is a view in perspective with portions of the vessel broken away to better disclose its construction;

Fig. 2 is a longitudinal vertical sectional view;

25 Fig. 3 is a longitudinal vertical sectional view of a modified form;

Fig. 4, is a detail fragmentary perspective view, partly in section, showing more clearly the recess in my preferred form.

30 A, represents the body of the receptacle, which is preferably made in two sections. The sections overlap at their edges, and are fastened together, preferably by means of staples 2, 2. A rim or band 3 is located 35 within the receptacle at the bottom edge thereof.

Staples 4, 4 are provided for fastening the rim in position. A removable bottom 5 is received upon the rim, and has frictional 40 engagement with the wall of the receptacle, which is preferably tapered, so that the bottom will have a tight fit when forced into the receptacle, thereby relieving some of the strain of supporting the bottom from the 45 rim 3.

The cover or lid is preferably constructed of two disks 6 and 7, the lower disk 6 being of less diameter than the upper disk. Interposed between the two disks are bars 8, 50 8 which enter recesses or notches 9 formed in the wall of the receptacle. The disks are connected to the bars by means of staples 10 for holding the bars in place and maintain-

ing the disks upon the bars. The lower disk 6 is adapted to be inserted within the receptacle and to engage the inner wall thereof, and the upper disk projects to the ends of the bars 8, so that it will rest upon the upper edge of the receptacle, and thereby prevent any possibility of moisture, snow, or 55 foreign matter from entering the receptacle or upon the lower member 6. With the bars arranged in this manner several receptacles can be stacked one upon the other without danger of crushing in the 60 heads or covers.

Ears 11, 11 are fastened to the receptacle through which a handle or bail may be fastened for carrying the receptacle.

In the structure shown in Fig. 3, the 70 bars 8 cross each other at their centers, and are fastened to the wall of the receptacle by means of nails 12. Seals 13 are pasted upon the receptacle over the nail heads, so that the nails cannot be withdrawn without 75 removing the seals, and thereby disclosing to the purchaser that the goods have been tampered with.

From the foregoing it will be seen that a receptacle is provided which can be made 80 of cardboard and the like with a removable bottom of like material, which is supported therein by friction and upon a rim located at the bottom of the receptacle, the cover or top which closes the other end of the receptacle being made in two pieces, so that the lower sectional disk thereof will have frictional engagement with the walls of the receptacle, and the upper disk will engage 85 the upper edge of the receptacle, whereby 90 the cover will be fitted to the receptacle, tightly and snugly, so that there will be no danger of any foreign matter entering the receptacle.

95 I claim:

1. In a receptacle, the combination with a tapering body, of a bottom received in said body, a cover consisting of two disks of different diameters, bars between said disks for spacing and holding the same, the disk 100 of smaller diameter being received within the body and having a frictional engagement with the tapering walls of said body, the upper disk being adapted to rest upon the upper edge of said tapering body, driven 105 means passing through said body into said

bars, and means for sealing said driven means.

2. A cover or lid for a receptacle comprising two disks of different size, and bars interposed between, brought to the outer edges of, and secured to said disks, whereby their ends may be utilized as means for fastening the cover to the receptacle when the smaller

disk enters the latter, and the larger disk rests upon its edge.

In testimony whereof I affix my signature, ¹⁰ in the presence of two witnesses.

HARRISON B. WALTER.
